UNITED STATES PATENT OFFICE.

WALTER E. MENDENHALL, OF LAKE CITY, COLORADO, ASSIGNOR TO THE UNION METALS EXTRACTION COMPANY, OF LAKE CITY, COLORADO, A CORPORATION OF COLORADO.

ORE CONCENTRATOR.

Application filed December 31, 1923. Serial No. 683,806.

To all whom it may concern:

Be it known that I, WALTER E. MENDENHALL, a citizen of the United States, residing at Lake City, in the county of Hinsdale 5 and State of Colorado, have invented a new and useful Improvement in Ore Concentrators, of which the following is a specification.

This invention relates to an ore concentrator by means of which metals, minerals 10 and other valuable materials may be recovered from alluvial deposits, sand, gravel, crushed ore or the like, and a rich concentrate obtained which will justify transportation to some available point for final treatment and separation.

The principal object of the invention is to provide improved mechanism by means 20 of which the separation is effected without the use of water, the separation being effected by utilizing the difference in the specific gravity in the constituent parts of the material. This feature is of especial value in arid regions and in other places 25 where water is difficult to obtain.

A more specific object of the invention is to provide concentrating means including a plurality of riffles arranged in series of banks and set at such a steep inclination 30 that the material to be treated will barely flow down over the riffles unaided, the riffles being provided with transverse channels, and means provided for jarring the riffles so that the particles having the greatest 35 specific gravity will settle to the bottom of the channels while the remaining portions pass on over the riffles. Each riffle may also be provided at one side with a slot extending throughout its length through 40 which the concentrate may be delivered.

The invention consists further in certain details of construction and combinations of elements which will be more fully explained in the following description taken in connection with the accompanying drawings, 45 in which:—

Fig. 1 is a front elevation of the invention viewed at an angle perpendicular to the plane of the riffles.

Fig. 2 is a central longitudinal section thereof.

Fig. 3 is a transverse section on the line 3—3 of Fig. 2.

Fig. 4 is a sectional detail view illustrat-

ing the jarring means at the upper end of 55 the device.

Fig. 5 is a sectional detail view showing the lateral jarring means.

Fig. 6 is a section taken on the line 6—6 of Fig. 2. 60

Fig. 7 is a detail view of one bank of riffles.

Fig. 8 is a section taken on the line 8—8 of Fig. 7.

Fig. 9 is a fragmentary view showing a 65 series of riffles of modified construction.

Referring in detail to the drawings, the riffle frame is mounted upon a base 10 and includes longitudinal side bars 11 and 12 connected at the top and bottom by cross 70 bars 13 and 14, respectively, between which the riffle box is mounted and supported by transverse rider bars 15.

The riffle box includes a rectangular 75 frame 16 having a plurality of longitudinal partitions 17 between which the riffles are secured, the riffles being supported by longitudinal cleats 18 in spaced relation to a bottom 19, of suitable material such as sheet metal, for receiving and delivering the concentrate. 80

As clearly shown in Figs. 1, 2 and 3, the riffles are arranged in a series of banks 20, 21 and 22, each bank consisting of a plurality of riffles arranged one above the other. 85 The several banks are arranged side by side and each riffle is provided with a series of transverse channels 23, the channels progressively increasing in width from one bank to the next. The riffles having the channels 90 of smallest width are preferably wider than those having channels of greater width.

It will be noted that the riffles are arranged and supported at an inclination 95 steep enough so that when the material is delivered thereto, it will barely flow downwardly over the same, and it is desirable that means be provided for adjusting this inclination so that the best results may be obtained with the specific material being 100 treated. This adjusting means may be in the form of screws, as indicated at 24, screws being provided at the upper and lower ends so that the inclination may be either increased or diminished, as necessary. 105

As the material flows downwardly over the riffles, the latter are jarred rapidly so that the particles having the greatest spe-

cific gravity will gradually work their way downwardly into the channels 23. It is preferable that the riffles be subjected to jarring both longitudinally and laterally. 5 The means which I have provided for effecting this purpose includes a plurality of stems 25 extending longitudinally above the riffle frame and supported in a head 26, the pins being extended through and guided by 10 the upper cross bar 13. The pins 25 are preferably provided at their lower ends with iron shoes 27 which are urged into contact with the upper side of the frame 16 by coiled springs 28 acting between the cross 15 bar 13 and head 26. Wear plates 29 are preferably provided in the frame 16 against which the shoes 27 engage. A shaft 30 is journaled in the sides of the supporting frame and provided with tappets or cams 31 20 for rapidly raising and suddenly releasing the stems 25 to permit the same to strike against the riffle frame and jar it. Suitable buffers 32 of rubber or the like are provided on the foot piece 14, which are designed to 25 give a slight resistance to the jar of the striking stems to prevent too sharp an up-throw of the material collected in the channels 23.

Similar stems 33, arranged horizontally 30 and supported by a head 34, are actuated in a similar manner by springs 35 and cams 36 on a shaft 37 to transmit a lateral jar to the riffle frame. The shafts 37 and 30 are connected by bevel gearing 38 and driven by a 35 drive pulley 39 or other suitable means which may be arranged on either one of the shafts. Coiled buffer springs 40 are preferably provided on the side of the frame 16 opposite the jarring stems 33.

40 In the form illustrated in Figs. 1 to 8, each of the riffles 20, 21 and 22 is spaced at one side from the adjacent partition 18 to form a slot 41 through which the concentrate is gradually discharged from the channels 23. The lower riffles project beyond the upper riffles, as shown at 42, so that the material, as it is discharged from one of the spouts 43 will be distributed to the several riffles of each bank. The ore concentrate, 45 as it is discharged through the slots 41, will drop onto the bottom 19 and be discharged at the lower end thereof through a suitable chute 44, while the worthless portion of the material will be discharged over the lower 50 ends of the riffles and may be removed to a dump.

It will be understood that as many riffles 55 may be used as desired, depending upon the capacity of the desired plant and upon the nature of the material to be treated. In Fig. 9, I have shown a modification in which, in addition to the banks of riffles 20^a, 21^a and 22^a, a fourth bank 45 is added in which the channels 23^a are very fine, this structure being 60 particularly adapted for the treatment

of fine silt or sand. In this figure, the slots at the sides of the riffles have been omitted. The operation of this form of riffle will be the same as the other form except that the operation will be stopped at intervals, in 70 order to remove the concentrate from the riffles, while in the form wherein the slots 41 are provided, the operation may be carried on continuously while the concentrate is continuously delivered by the floor 19 and chute 75 44.

Any suitable means may be provided for delivering the material to the several riffles, one form of such mechanism being shown in Fig. 1, wherein a rotatable sizing 80 screen 46 is provided into which the material is poured through a chute 47. Screens 48, 49 and 50, of suitable sized mesh, may be provided for sizing the material, as many different screens being provided as there are 85 riffles. The material, as it passes through the screens will be transferred through the several chutes 43, to the respective banks of 90 riffles.

In the practical operation of the invention, a plant will be provided with a suitable number of riffles to provide the desired capacity, the riffles being of the several sizes adapted best to deal with the particular kind of material being treated. The jarring 95 stems 25 and 33 and the springs 28 and 35, will be adjusted to deliver blows of the desired strength, and the inclination of the riffle frame will be adjusted by the thumb screws 24 so as to give the best results for 100 the character of the ore being treated.

The riffles and the framework supporting the same may be constructed of wood, steel or any other material which is economical, efficient and durable. When properly installed and adjusted, the invention will produce a rich concentrate by the mechanical application of the law of gravity without the use of water.

While I have shown and described the 110 specific details of the mechanism by means of which the principles of the invention are carried out, it is apparent that numerous modifications may be made therein so long as there is no material departure from the 115 salient features of the invention.

What is claimed is:

1. In an ore concentrator, the combination of a bank of riffles set at an inclination and having transverse channels, frames in which the riffles are mounted, the riffles being spaced from the frames at one side to provide a slot at the side of each riffle through which the concentrate is discharged, means for adjusting the inclination of the riffles 120 in accordance with the material being treated so that the latter will barely flow down the inclination unaided, and means for jarring the riffles while the material flows over the same.

2. In an ore concentrator, the combination of a bank of riffles set at an inclination and arranged one above the other, said riffles having transverse channels in their upper faces, means for adjusting the inclination of the riffles in accordance with the material being treated so that the latter will barely flow down the inclination unaided, means for delivering material to all the riffles simultaneously, means for jarring the riffles while the material flows over the same, and frames in which the riffles are mounted, each riffle being provided with a slot at one side thereof through which the concentrate is discharged.
3. In an ore concentrator, the combination of an inclined frame containing riffles, means for striking sharp blows against the end of the frame to jar the riffles in the direction in which the ore passes over the same, other means for striking sharp blows against the side of the frame to jar the riffles laterally, and means connecting both of said jarring means for simultaneous operation.
4. In an ore concentrator, the combination of a plurality of superposed frames containing riffles set at an inclination and having transverse channels, means for feeding material to the upper ends of said frames, means for adjusting the inclination of the frames in accordance with the material being treated so that the latter will barely flow down the inclination unaided, and means for striking blows longitudinally and laterally against the frames to jar the same while the material flows over them.
5. In an ore concentrator, an inclined frame containing a plurality of riffles, jarring members mounted for rectilinear reciprocation in the plane of the frame, a shaft having cams operable upon rotation of the shaft to retract the jarring elements, and springs operable to advance said elements and cause them to strike against the frame as soon as they are released by the cams.
6. In an ore concentrator, the combination of a frame set at an inclination and having transverse channels forming riffles, means for adjusting the inclination of the frame in accordance with the material being treated so that the latter will barely flow down the inclination unaided, and means for striking blows longitudinally and laterally against the frame to jar the riffles while the material flows over the same.
7. In an ore concentrator, the combination of a plurality of riffles set at an inclination and each having transverse channels across its upper face and a longitudinal slot through one side thereof, means for adjusting the inclination of the riffles in accordance with the material being treated so that the latter will barely flow down the inclination unaided, means for delivering material to all the riffles simultaneously, and means for jarring the riffles longitudinally and transversely while the material flows over the same.
8. In an ore concentrator, a series of banks of riffles set at an inclination and arranged side by side, the riffles of each bank being arranged one above the other, said riffles having transversely-extending channels, the width of the channels increasing progressively from one side to the other of the series, means for grading the material into different sizes proportionate to the width of the channels and delivering the same to the respective riffles, and means for jarring the riffles as the material flows over the same.
9. In an ore concentrator, a plurality of riffles arranged in banks side by side, the riffles of each bank being superposed and spaced apart, each riffle being provided with transverse channels, the width of the channels increasing progressively from one bank to the next, means for grading the material into different sizes proportionate to the width of the channels and delivering the same to the respective riffles, and means for jarring the riffles as the material flows over the same.
10. In an ore concentrator, a plurality of banks of superposed riffles having transverse channels in their upper faces, the several banks being arranged side by side and the width of the channels increasing progressively from one bank of riffles to the next, frames for supporting the riffles and provided with slots adjacent the riffles at one side whereby the concentrate may be continuously delivered from the channels, means for grading the material into different sizes proportionate to the width of the channels and delivering the same to the respective riffles, and means for jarring the riffles longitudinally and transversely as the material flows over the same.
11. In an ore concentrator, a plurality of inclined riffles having transverse channels therein, the channels of certain of said riffles being of different width than those of certain of the other riffles, means for separating the ore into different sizes and delivering it to the respective riffles according to the different sized channels, and means for jarring the riffles as the ore passes over the same.
12. In an ore concentrator, an inclined frame containing a riffle, spring-held jarring members adapted to deliver blows to the frame, a shaft having cams operable upon rotation of the shaft to rapidly retract the jarring elements against the action of the springs and to suddenly release the same to strike against one side of the frame, yieldable buffers in constant contact with the other side of the frame, and means for rotating said shaft.

13. In an ore concentrator, an inclined rectangular frame containing a plurality of riffles arranged side by side and having transverse channels, the channels in each riffle being of different width than the channels in the adjacent riffle, spring-held jarring members at the top and one side of the frame adapted to deliver blows to the frame, a pair of shafts arranged at the top and one side of the frame respectively, and having cams operable upon rotation of the shafts to rapidly retract the jarring elements against the action of the springs and to suddenly release the same to strike against the frame, spring buffers in constant contact with the opposite side of the frame, and soft cushions at the bottom of the frame against which the same rest by gravity, and means for rotating said shaft.
14. In an ore concentrator, an inclined rectangular frame, spring-held jarring members at the top and one side of the frame adapted to deliver blows to the frame, a pair of shafts arranged at the top and one side of the frame respectively, and having cams operable upon rotation of the shafts to rapidly retract the jarring elements against the action of the springs and to suddenly release the same to strike against the frame, spring buffers in constant contact with the opposite side of the frame, and cushions at the bottom of the frame against which the same rest by gravity, and means for rotating said shafts.

In testimony, that I claim the foregoing as my own, I have hereto affixed my signature.

WALTER E. MENDENHALL.
